UNITED STATES PATENT OFFICE.

LEON N. BOURDEAU, OF ROCK ISLAND, ILLINOIS.

CURTAIN STRETCHER.

Application filed December 3, 1923, Serial No. 678,327. Renewed November 17, 1926.

My invention has reference to curtain stretchers, and has for its chief purpose to provide a simple frame, which can be reduced to a compact space, and in which the curtains can be supported without the employment of injurious and flesh-piercing pins, such as are in common use in machines of this kind. This is accomplished by providing the ends of the curtains with rods, and supporting such rods in spaced relation with the curtains in extended position between the same.

Another purpose of the invention is to provide supporting means for the curtain rods, capable of adjustment, to first properly space such rods, and to next give the desired tension to the curtains, in which supports the rods can be held in suitable spaced relations, so that the curtains may be held at a desired distance from each other, in the stretching and drying operation.

Another purpose of the invention is the provision of means for engagement with the side edges of the curtains which are in position in the machine, in cases where such edges require straightening.

The above-named, and other features and advantages of the invention will more fully appear from the following specification, taken in connection with the accompanying drawings, in which:

Fig. 1 shows the device in front elevation, in open position.

Fig. 2 is a side view thereof.

Fig. 3 is a detail of one of the supporting arms 24.

Fig. 4 is an end view of the arm 24.

Fig. 5 is an end view of the clamp-bars 35.

Fig. 6 is a fragmentary detail of the inner face of one of said bars.

Fig. 7 is a perspective view of one of the clips 42, detached.

Fig. 8 is a detail, showing a combination attachment, embracing a clothes supporting device.

The main frame of the device consists of a pair of side pieces 1 and 2, united at their upper ends by a pair of braces 3 and 4, pivoted to said side-pieces at their ends, and united at a central point by a bolt 5, fitted with a thumb-turn 6. The lower ends of the side-pieces are similarly united by braces 7 and 8, pivoted at their outer ends to said side pieces, and united by a bolt 9, provided with a thumb-nut 10. When the thumb-nuts 6 and 10 are tightened a prac-

tically rigid rectangular frame is formed, and upon loosening such nuts, the upper braces can be folded downwardly, and the lower braces upwardly, bringing the side-pieces into position adjacent to one another. When in open position the frame is further held from collapsing by a brace 11, pivoted at one end to the side-piece 2, and detachably connected with the brace 4, and a brace 12, pivoted to the side-piece 1, and detachably secured to the brace 7. Upon being detached the braces 11 and 12 can be folded against the respective side-pieces.

The side-pieces 1 and 2 are supported in a vertical position by means of feet 13, pivoted to the side-pieces at their rear ends, and held from closing against same by braces 14, pivoted to the side-pieces at their upper ends, and detachably connected with the feet 13 at their lower ends. When it is desired to store the device, the braces 14 can be disconnected from the feet, and folded upwardly against the side-pieces, and the feet 13 similarly folded upwardly.

To opposite sides of the feet 13 are pivoted short uprights 15 and 16, the upper ends of which are connected with the braces 14 by means of bolts 17, provided on their outer ends with thumb-nuts 18, and spaced apart from the side-pieces 1 and 2 are similar uprights 19, connected therewith by bolts 20, fitted on their ends with thumb-nuts 21. In the spaces between the uprights 15 and 16, and the uprights 19 and the side-pieces 1 and 2, are bars 22, provided in their lower edges with spaced notches 23. By operation of the thumb-nuts 18 and 21 the outer posts 16 and 19 can be clamped tightly against the ends of the bars 22, to hold them securely in horizontal position. Secured to the side-pieces 1 and 2, near the upper ends thereof, are arms 24, held in adjustable positions on said side-pieces by means of blocks 25 and 26, fixed to the ends of said arms, and provided with inner curved faces which bear against the edges of said side-pieces. When the arms 24 are in a substantially horizontal position said blocks tightly engage the side pieces, and hold the arms from downward movement, but by elevating the outer ends of the arms slightly the blocks move freely on said pieces, permitting the placing of the arms in adjusted positions thereon. Said arms are held from accidental release by means of bars 27, pivoted to the blocks 25, as at *a*, and secured at their

opposite ends by bolts 28 in the blocks 26. When it is desired to pack the parts of the frame together, the arms 24 can be disconnected, and placed against the main frame.

5 The arms 24 are provided with openings 29, corresponding in number with the notches in the bars 22, and in vertical alignment therewith. Said openings are adapted to receive and hold rods 31, for the support of a curtain, as indicated at 32, the rod being extended through the hem in the end of such curtain. A similar rod 33 is inserted in the hem in the opposite end of the curtain, and is held at its ends in two of the notches 23 which are in register with each other. While in this position the curtain is thoroughly dried, under a desired amount of tension.

10 In positioning the curtain, the upper rod is first placed in the openings 29, and the arms 24 raised or lowered until the rod 33 can be easily engaged with the bars 22. The nuts 18 and 21 are then loosened and the bars 22 forced downwardly until the requisite amount of tension is given to the curtain, whereupon the nuts are again tightened, holding the curtain in its stretched position. Two or more curtains can thus be supported in the frame at the same time, with sufficient space between the same for a satisfactory circulation of the air, and to prevent the curtains from being in contact with each other. In removing the curtains the above operation is reversed.

15 The side-pieces of the frame are of sufficient height to support curtains of any length, and persons of shorter stature can easily place the same in position by lowering the arms 24 to any desired extent on the side pieces, placing the supporting rods in position in said arms, and moving them again upwardly to their usual position.

20 In the majority of cases, in supporting the curtains at the ends, the sides thereof will remain straight, but in some cases it is necessary to make use of auxiliary means for preventing said sides from getting out of proper position. I therefore provide clamp-pieces for the sides of the curtains, consisting of companion strips 35, adapted to be held together at intervals by spring clips 36. The edges of the curtain are placed between these strips, as shown in Fig. 1, and are held from release by said clips. 25 A further means for preventing accidental release of the edges of the curtain consists in a corrugated strip 37 on the inner face of one of the strips. If it is desired to give a lateral tension to the curtain this can be 30 accomplished by connecting the strips 35 with vertical bars 38, by means of small chains 39, attached at intervals to the clamping members, and detachably connected with said bars. The bars 38 are held at their upper ends in one of a series of notches in

35 arms 40, supported horizontally from the upper ends of the side-pieces 1 and 2, and at their lower ends in registering notches in pieces 41 attached to the lower ends of the uprights 16 and 19. The clamping members 40 on the edges of two or more adjacent curtains can be supported from one of the bars 38, if desired. By proper adjustment of the chains 39 on the bars 38 the curtains can be drawn into a taut condition, laterally, and the edges of said curtains held in such manner as to insure their being perfectly straight upon being removed from the frame.

40 In place of the arms 40, clips 42 can be attached to the arms 24, said clips having outward extensions 43, containing recesses 44 to receive the bar 38.

45 At 45 is shown an auxiliary arm, adapted for support on the side-pieces, similarly to the arms 24, and provided with a series 50 of openings 46. This can be used for holding the ends of rods which are employed in the support of relatively shorter curtains, it being possible to stretch both long and short curtains in the frame at the same time. In this use, the forward notches 23 in the bar 22 would be employed with corresponding openings 29 in the arm 24, and the rear notches with the openings in the arm 45. Said arm 45 is capable of vertical adjustment on the side-pieces, similarly to the arms 24.

55 In Fig. 8 is shown a block 47, also slideable on the side-pieces 1 or 2, and provided with prongs 48, which can be used for the support of garments or other articles.

60 What I claim, and desire to secure by Letters Patent, is:

1. A device of the class described, comprising a rectangular frame, provided with spaced apart side-pieces, connected by foldable braces; rod-supporting arms slidably adjustable on said side-pieces; clamping frames at one end of said side-pieces; and rod-holding bars, secured in said clamping frames, and capable of a limited adjustment therein, with relation to said arms. 105

65 2. A device of the class described, comprising a rectangular frame, formed of a pair of spaced-apart side-pieces, connected by foldable braces; foldable feet for said side-pieces, and foldable braces therefor; rod supporting arms supported horizontally on the upper parts of said side-pieces, and capable of a sliding adjustment thereon; clamping frames supported on said feet; and rod-holding bars, secured horizontally in said clamping-frames, so as to be capable of a limited adjustment therein, vertically, 110 and in alignment with said rod-supporting arms. 120

70 3. A device of the class described, comprising a rectangular frame, formed of a pair of spaced-apart side-pieces, connected by foldable braces; rod-supporting arms 125

horizontally supported on the upper ends of said side-pieces, so as to be slidably adjustable thereon; clamping frames at the lower ends of said side-pieces; rod-supporting bars secured in said clamping frames, and capable of a limited vertical adjustment therein; and auxiliary rod-supporting arms, also slidably adjustable on said side-pieces, and capable of cooperating with said rod-

10 supporting bars.

4. A device of the class described, comprising a frame, formed of spaced-apart side-pieces, provided at their lower ends with suitable supporting means; arms sup-

15 ported from the upper parts of said side-pieces, so as to be vertically adjustable thereon, and capable of supporting a plurality of curtain rods; bars supported near the lower ends of said side-pieces, also capa-

20 ble of adjustment vertically, adapted to hold a plurality of curtain rods, in alignment with the first-named rods; clamping-bars adapted for engagement with the edge of a curtain; and means for the support of such

25 clamping-bars at the sides of said frame.

5. A device of the class described, comprising a frame, formed of spaced-apart side pieces, connected by foldable braces, and provided at their lower ends with suit-
30 able supporting means; arms supported horizontally from the upper parts of said

side-pieces, so as to be vertically adjustable thereon, and capable of supporting a plurality of curtain-sustaining rods, in spaced relations; bars supported horizontally near 35 the lower ends of said side-pieces, also capable of vertical adjustment, and adapted to hold a plurality of curtain-rods, to co-operate with said first-named rods; bars removably supported in a vertical position at 40 the sides of said side-pieces; and clamping-bars connected with said last-named bars, so as to be adjustable with relation thereto, and capable of embracing the edge of a curtain supported in said frame. 45

6. A device of the class described, comprising a frame, formed of spaced-apart side-pieces, connected by foldable braces, and provided at their lower ends with foldable supporting members; arms supported 50 horizontally from said side-pieces, and slidably adjustable thereon, said arms being provided with spaced rod-supporting openings; clamping frames at the lower ends of said side-pieces; and horizontal bars held 55 adjustably in said clamping frames, and provided with spaced rod holding openings in alignment vertically with the openings in said arms.

In testimony whereof I affix my signature.

LEON N. BOURDEAU.
